UNITED STATES PATENT OFFICE.

JOHN SARDO AND PATSY PARISO, OF ELMIRA, NEW YORK.

MICROMETER.

1,333,453.

Specification of Letters Patent. Patented Mar. 9, 1920.

Application filed November 3, 1918. Serial No. 261,661.

To all whom it may concern:

Be it known that we, JOHN SARDO and PATSY PARISO, citizens of the United States, residing at Elmira, in the county of Chemung and State of New York, have invented new and useful Improvements in Micrometers, of which the following is a specification.

The object of the invention is to provide a new and novel form of micrometer designed for internal as well as external measurements, whereby the internal diameter of tubing or the internal diameter of holes, bores and the like may be readily and accurately determined. To this end the invention comprises attachments for the spindle and anvil of a micrometer gage which attachments may be readily removed when not in use.

Other and further objects of the invention appear in the following description wherein the invention is set forth in detail.

To the exact construction in which it is shown, and described, the invention is not to be restricted. The right is reserved to make such changes or alterations as the actual reduction to practice may suggest, in so far as such changes or alterations are comprehended in spirit by the annexed claims.

In the accompanying drawings, wherein like numerals of reference designate like parts,

Figure 1 is a view in side elevation of the improved micrometer.

Fig. 2 is a section on the line 2—2 of Fig. 1 with the yoke broken away.

Fig. 3 is a similar section on the line 3—3 of Fig. 1.

Fig. 4 is a section on the line 4—4 of Fig. 1.

Fig. 5 is a section on the line 5—5 of Fig. 1.

Referring to the drawings, the invention is shown as comprising a micrometer gage similar to the conventional tool of this character, the gage comprising the yoke 1, the spindle 2, the sleeve 3, the thimble 4, and the anvil 5. The spindle, as is usual, is threadingly engaged in the yoke, but the latter is provided with the extension 6 projecting laterally as regards the spindle. This extension 6 at its end is formed with the double tubular bearing member 7, the two elements of which are parallel, so that each may slidably receive a stud 8 carried by the body portion 9 of a measuring element generally designated 10, the latter being provided with

the finger 11 at the terminus of which there is an upturned measuring lip 12, the latter being rounded to permit accuracy of measurement in the gaging of concaved surfaces, such as the attachment is designed to assist in measuring. The body portion 9 of the element 10 adjacent that end remote from the finger carries a disk 13, the latter being provided with annular flanges 14 which engage the body member both on the upper and lower surfaces. This construction provides for rotary movement of the disk relative to the body portion but precludes its movement in an axial direction relative thereto. This disk 13 is engageable with the free end of the spindle 2, a hole being provided through which a screw 16 may pass and threadingly engage a tapped hole formed in the free end of the spindle 2. A second measuring element 17 is provided for attachment to the anvil 5, the latter being bored longitudinally to permit a screw 18 to be passed through it and to threadingly engage the body portion 19 of the element 17, the body portion being formed with a transversely disposed rib 20 which engages a similar slot formed in the anvil. Thus angular movement of the element 7 on the anvil is precluded. The element 17 is, as is the element 10, provided with a finger 21, this finger terminating in the downturned measuring lip 22 also rounded off as is the lip 12 for the purpose of accuracy in measurement during the gaging or measuring of concave surfaces.

It is obvious that the device may be used for measuring diameters of holes and the like as well as for exterior measurement, the latter being gaged, if necessary, with the interior measuring elements in place. Such exterior measurements may be readily effected between the bottom face of the finger 11 and the top face of the finger 21, due consideration being given to the manner in which these parts extend the length of the spindle and of the anvil and thereby affect the scale on the sleeve.

When any exterior measuring is to be done, however, both the measuring elements 10 and 17 may be removed, simply by the removal of the screws 18 and 16, when the gaging is accomplished directly with the spindle and anvil as is usual with this character of gage.

In the foregoing description and the ac-

companying drawings, it is believed that the invention has been clearly enough set forth to render further description unnecessary.

The invention having been described what is claimed as new and useful is:

1. A tool of the kind described comprising the combination with the yoke, spindle and anvil of a micrometer, the yoke having an extension formed adjacent the spindle, of a double tubular bearing element formed with said extension, an internal measuring element having a body attachable to the spindle, studs carried by said body and slidably engaging the units of said double bearing element, the body being formed with a finger having a measuring lip at its free end, and a second measuring element having a body attachable to the anvil, the said second measuring element also being formed with a finger having a measuring lip at its end.

2. In a tool of the kind described, the combination with a micrometer having a yoke, a spindle and an anvil, the yoke adjacent the spindle being formed with a slide bearing element, of internal measuring elements detachably secured to the spindle and anvil respectively, the said measuring elements projecting laterally with respect to the anvil and spindle, the element connecting with the spindle having sliding means engageable with said slide bearing.

3. A tool of the kind described comprising the combination with the yoke, spindle and anvil of a micrometer, of a measuring ele-

ment formed with a finger and having a measuring lip at the free end of said finger, the said measuring element being detachably secured to the anvil, a second measuring element formed with a body and also having a finger with a measuring lip at the end thereof, a disk rotatably mounted in the body, means for detachably securing said disk to said spindle, and means carried by the body and slidably engaging the yoke to preclude angular movement of the body and its finger when the spindle is being rotated.

4. A tool of the kind described comprising the combination with the yoke, spindle and anvil of a micrometer, of a measuring element formed with a finger and having a measuring lip at the free end of said finger, the said measuring element being detachably secured to the anvil, a second measuring element formed with a body and also having a finger with a measuring lip at the end thereof, a disk rotatably mounted in the body, a screw passing through the disk and threadingly engaging the spindle, the yoke being formed with an extension providing a double tubular bearing member, and studs secured to the body portion of said second measuring element and slidably engaging in the units of the double tubular bearing member.

In testimony whereof we affix our signatures.

JOHN SARDO.
PATSY PARISO.
